UNITED STATES PATENT OFFICE.

FRANK F. SMITH, OF DETROIT, MICHIGAN, ASSIGNOR TO THE ROBERT MITCHELL MACHINERY CO., OF DETROIT, MICHIGAN, A CORPORATION OF MICHIGAN.

LIP-TURNER.

No. 809,332.

Specification of Letters Patent.

Patented Jan. 9, 1906.

Application filed May 10, 1902. Renewed November 4, 1904. Serial No. 231,356.

To all whom it may concern:

Be it known that I, FRANK F. SMITH, a citizen of the United States of America, residing at Detroit, in the county of Wayne and State of Michigan, have invented certain new and useful Improvements in Lip-Turners, of which the following is a specification, reference being had therein to the accompanying drawings.

10 My invention relates to improvements in that class of shoe-making machinery known as "lip-turners," and its object is to provide a machine which will lift, turn, and "set" the lip, so that it will project at right angles to the sole without cutting, tearing, or otherwise injuring the lip in the operation, it also being an object of the invention to provide a machine which may be used on either "Mc-Kay" or "welt" work and which will effectually turn the lip on soles of any shape or thickness or upon those which have been previously molded in a form.

25 To this end the invention consists in providing a work supporting and feeding wheel which is detachable and made interchangeable with others of a different construction for use upon the different kinds of work, a lip-raising guide, a wiper-wheel revolving in a plane at right angles to the path of the lip 30 and having teeth to engage the lip, and a roll adjacent to the wiper-wheel.

35 The invention also consists in providing the device with certain other new and useful features and in the peculiar arrangement and combination of parts, all as hereinafter more fully described, and particularly pointed out in the claims, reference being had to the accompanying drawings, in which—

40 Figure 1 is a perspective view of a device embodying my invention; Fig. 2, a longitudinal vertical section of the same, showing a modified form of work-support attached; and Fig. 3 is an edge view of a modified form of work-supporting wheel.

45 A represents the base portion of the frame of the machine, and A' and A² two vertical standards or posts extending upward from the base, one at each end thereof, the standard A' being hollow at its lower end and 50 formed with vertical ways A³, on which ways is the bearing-block B, in which the shaft C is journaled near one end, its opposite end being journaled in the bearing-block C',

loosely held in an opening in the standard A². The block B is vertically movable on its ways 55 and is held in its upper position in engagement with the stops B' by a spring D, which engages its lower side and extends downward within the hollow portion of the standard A' to engage an adjusting-plug D', adjustably 60 held in an opening into the bottom of the standard by adjusting-screws D², said block being moved along its ways by a rod D³, attached to the lower side thereof and passed down through the axis of said spring and of 65 said plug, where it is adapted to be connected to a suitable foot-lever or other operating mechanism at its lower end. The end of the shaft C adjacent to the block B is reduced, and on this reduced portion is secured a feed- 70 wheel E by a nut on the end of the shaft, a sleeve on the shaft between the wheel and the block preventing said shaft from moving longitudinally in one direction and a gear-wheel F on the opposite end of said shaft in 75 engagement with the opposite block C' preventing said shaft from moving in the other direction. The face of the feed-wheel E is provided with a band of rubber E' to form a friction-surface to engage the sole to be operated upon and feed the same forward.

80 A tool-supporting block G is secured between the upper ends of the ways A³ by the flanges G', which engage the ways at one side, and the cross-bar G², which engages the opposite side of the ways and has a binding-screw G³ extending through the bar and engaging a screw-threaded opening in the block 85 to bind the flanges and bar against the sides of the ways and adjustably secure the block 90 to the standard, which block is extended to form a seat for the tool H, which tool is adjustably secured to the upper face thereof by the set-screw H' passing through a slot H² in said tool. The outer end of the tool is 95 grooved or cut away transversely to form a shoulder H³ to engage the under side of the lip and lift the same, and the feather or portion from which the lip is severed is firmly clamped between the wheel E and the lower 100 side of said shoulder, said tool at the same time serving as a guide against which the sole is held.

105 Secured to the upper end of the standard A' by a set-screw I', passing through a slot in said standard, is a bracket I, which bracket is

provided with a bearing in which is journaled a shaft J, extending at right angles to the shaft C, and upon one end of which shaft J is a pulley J', and upon the other end is secured a 5 wiper-wheel K, revolving in a plane at right angles to the plane in which the feed-wheel E revolves, said wheel K being provided with wiper-teeth K', the contact sides and edges of which are rounded off to prevent the cutting 10 of the lip.

To one side of the tool-block G is adjustably secured the bracket L' by set-screws L² passing through vertical slots in the bracket, and upon this bracket is journaled the presser-roll L, which extends longitudinally parallel 15 with the plane in which the wiper-wheel revolves and adjacent to it to engage the lip after it has been turned by the wiper-wheel and press or roll the same down to set it, thus 20 removing all tendency to spring back to its original position.

It is necessary that the relative positions 25 of the wiper-wheel K and the tool H be accurately determined, so that the wiper-teeth will strike the lip at the proper place, and to aid in this adjustment the bracket I and block G are each provided with an ear I², and an adjusting-screw I³ passes through an opening in one of the ears and engages a 30 screw-threaded opening in the other, so that when the set-screw I³ is loosened the turning of the screw I³ will accurately determine the movement of the bracket.

A stub-shaft M is secured to the standard 35 A² near its lower end, and on this shaft is journaled a pinion N', which meshes with the gear-wheel F and transmits motion thereto from the drive-wheel N, which is secured to said pinion and also mounted on said shaft, 40 and to the upper end of said standard is adjustably secured a bracket O by a set-screw O' passing through a slot in the bracket and an adjusting-screw O² engaging the upper end of the standard to raise and lower the 45 bracket, on which bracket is journaled two idlers O³, over which the driving-belt P passes to transmit motion from the drive-wheel N to the pulley J' to actuate the wiper-wheel K.

In the modification of the work supporting and feeding mechanism shown in Fig. 2 50 a bevel-gear Q is substituted for the feed-wheel E, and a bracket Q', which is made detachable by being secured to the standard A' by screw-bolts, extends outward beyond the end of the shaft C and is provided with a bearing for the vertical shaft R', upon the upper end of which is secured to revolve in a horizontal plane the feed wheel or table R, the lower side of said table being provided 55 with a gear R² to mesh with the gear Q. A spring S is sleeved on the lower end of the shaft and held thereon by a pin S' passing through the shaft, the bracket being recessed to receive the spring and to furnish a shoulder against which it abuts. The shaft R' 60

has a free longitudinal movement in its bearing, and the spring S holds the gear R² in mesh with the gear Q as the latter rises and falls, and so the table R is supported and revolved by the gear Q and pressed yieldingly 70 upward by the spring D to clamp the feather of the sole between its upper face and the tool H. The upper face of this wheel or table R is provided with a peripheral groove, in which is secured a band of rubber R³ to form a frictional contact-surface to prevent the sole from slipping. This horizontal work supporting and feeding wheel is used when the sole or insole to be operated upon is thin and flexible, and therefore requires an extended 80 supporting-surface to hold it up in a position to be effectively operated upon by the wiper-wheel and presser-roll. The feed-wheel E, operating in a vertical instead of a horizontal position, contacts the sole at one point only, 85 which is directly beneath the tool H, and therefore if the sole is very flexible the presser-roll L would have little effect on the lip, as the sole would not be supported directly beneath the said roll to hold it in contact 90 therewith; but when the sole is quite rigid and thick the point at which the sole is supported is so nearly directly beneath the roll that the lip will be effectually rolled down.

On work where to roughen the surface contacted by the work supporting and feeding wheel will do no harm, such as McKay work, a positive feed may be used, as shown in Fig. 3, which consists in forming the wheel S of outer disks S' and S², the disk S' being 95 formed with a hub portion, and thin inner disks S³ of slightly larger diameter, between which is interposed the thin separating-disk S⁴, which disks S³ are provided with teeth at their periphery and are firmly clamped between the outer disks in such a position that their teeth will not coincide, but will be 100 "staggered"—that is, the teeth on one wheel will project outward at a point intermediate that of the teeth on the other disk; but on 105 work where it is necessary that the surface be left perfectly smooth the rubber band is preferably used, and this form may be used in all cases except where the sole feeds through 110 particularly hard.

By using a feed-wheel which revolves in a vertical plane to support the work the lips on soles which have been formed in a mold may be turned, and by employing a thin wheel to wipe or turn the lip the tool for raising the 115 lip, the wheel for turning, and the roll for pressing it down may all lie very close together, and thus take up little space, so that in turning the lip on a pointed-toed sole the wheel and roll will not be thrown out of engagement with the lip in going around the toe. The wiper-wheel revolving at right angles to the path of the lip has a lifting and 120 wiping action, which breaks the lip over, but 125 cannot in any way cut or injure it, the teeth 130

being rounded or inclined opposite to the direction of revolution and also having their sides which contact the lip rounded off.

The several parts are all made adjustable, 5 and by providing interchangeable work supporting and feeding wheels the machine may be employed to effectually turn the lips on any kind of work, and a simple, cheap, and very efficient machine is secured.

10 Having thus fully described my invention, what I claim is—

1. In a lip-turning machine, the combination with means for supporting and feeding the work, of a wiper-wheel revolving in a 15 plane at right angles to the path of the lip and having peripheral wiper-teeth traversing the path of the lip.

2. In a lip-turning machine, the combination with means for supporting and feeding the work, of a wiper-wheel revolving in a 20 plane at right angles to the path of the lip and having peripheral wiper-teeth traversing the path of the lip above the surface of the work.

25 3. In a lip-turning machine, the combination with means for supporting and feeding the work, of a revolving wiper-wheel operating in a plane at right angles to the path of the lip for turning the lip and a presser for setting the lip after passing the wiper-wheel.

30 4. In a lip-turning machine, the combination with means for supporting and feeding the work, of a lip-raising tool, a wiper-wheel traversing the path of the lip for turning the lip and a presser-roll for setting the lip.

35 5. In a lip-turning machine, a revolving wiper-wheel in a plane at right angles to the path of the lip and having wiper-teeth formed with rounded-off contact-faces for striking the lip above its base and turning the same.

40 6. In a lip-turning machine, the combination with means for supporting and feeding the work, of a wiper-wheel revolving in a plane at right angles to the path of the lip and adapted to turn the lip by a wiping contact therewith and means for holding the work in position against such contact.

45 7. In a lip-turning machine, in combination with the frame thereof, a lip-raising tool mounted upon the frame, a wiper-wheel revolvable in a plane at right angles to the path of the lip and adjacent to said tool, a presser-roll adjustably secured to said frame and extending longitudinally across the path of the 50 lip, a work-supporting wheel revolvable in a vertical plane, and means for yieldingly holding said wheel in contact with the work to clamp the same between the tool and the wheel.

55 8. In a lip-turning machine, in combination with the frame thereof, a horizontal shaft mounted in movable bearings on said frame, a work supporting and feeding wheel on said shaft, a lip-raising guide adjustably secured to the frame, a wiper-wheel revolving at 60 right angles to the path of the lip and adja-

ing the shaft to clamp the work between the wheel and said guide, a bracket adjustably secured to the frame, a shaft mounted on said bracket, a wiper-wheel on said shaft adjacent to the guide, and a presser-roll adjacent to the wiper-wheel. 70

9. In a lip-turning machine, in combination with the frame thereof having vertical ways, a bearing-block mounted on said ways, a shaft extending longitudinally of the frame 75 and journaled and supported at one end on said block, a work supporting and feeding wheel on said shaft, a lip-raising guide on said frame extending over said wheel, a spring engaging said bearing-block to yieldingly clamp 80 the work between the wheel and the guide, means for depressing said spring to lower the wheel, a bracket secured to the frame, a shaft mounted in a bearing on said bracket, a wiper-wheel revolving in a plane at right angles to the path of the lip and secured on the 85 end of said shaft, and a bracket adjustably mounted on the frame adjacent to the wiper-wheel and provided with a presser-roll extending across the path of the lip at right angles thereto. 90

10. In a lip-turning machine, in combination with the frame thereof, a bearing-block movable in vertical ways on said frame and a bearing-block secured in an opening in said 95 frame and free to tilt therein, a horizontal shaft mounted in said bearings, a work supporting and feeding wheel on said shaft, a lip-raising guide on said frame, a spring engaging the lower side of the movable bearing-block to hold the feed-wheel in contact with the work to clamp the same between the wheel and said guide, an adjusting-plug engaging the lower end of said spring, means for adjusting and holding said plug, a rod secured to said movable block to move the same on its ways, and a wiper-wheel adjacent to the lip-raising guide revolving at right 100 angles to the path of the lip. 105

11. In a lip-turning machine, in combination with the frame thereof having a vertical standard at each end thereof, one standard being provided with an opening and the other with vertical ways, a bearing-block in said opening and a bearing-block movable on said 110 ways, a horizontal shaft mounted on said blocks, a work supporting and feeding wheel on said shaft, stops adapted to be engaged by the block on said ways, a coil - spring engaging the lower side of said block at one end, an 115 adjusting-plug projecting through an opening in said frame and engaging the lower end of said spring and provided with an axial opening, means for adjusting said plug in the opening, a rod secured to the lower side of the 120 block on the ways and extending downward through the spring and the opening in the plug, a lip-raising guide adjustably secured to the frame, a wiper-wheel revolving at 125 right angles to the path of the lip and adja- 130

cent to the guide, a bracket adjustably secured to the frame, and a pressure-roll journaled on said bracket adjacent to the wiper-wheel.

- 5 12. In a lip-turning machine, in combination with the frame thereof having vertical standards, a horizontal shaft mounted in movable bearings on said standards, a work feeding and supporting wheel secured on
10 said shaft, a supporting - block adjustably secured to one of the standards, a lip-raising guide provided with a slot and adjustably secured to said block by a screw passing through said slot, a bracket adjustably secured to the block, a presser-roll journaled on
15

20 said bracket and extending longitudinally across the path of the lip, a bracket adjustably secured to the standard, a shaft mounted in a bearing on said last-named bracket, and a wiper-wheel secured to one end of the 20 last-named shaft and revolving in a plane at right angles to the path of the lip and between the lip-raising guide and the presser-roll.

25 In testimony whereof I affix my signature in presence of two witnesses.
